CLAIM

The ornamental design for column trim, as shown and described.

DESCRIPTION

FIG. 1 is a top left perspective view of column trim showing our new design;

FIG. 2 is a top view thereof;

FIG. 3 is a bottom view thereof;

FIG. 4 is a right side view thereof;

FIG. 5 is a left side view thereof;

FIG. 6 is a front side view thereof; and,

FIG. 7 is a back side view thereof.

The uniform broken line showing in FIGS. 1 and 3-7 is for the purpose of illustrating portions of the column trim and forms no part of the claimed design.

1 Claim, 7 Drawing Sheets(56)
